Patented Sept. 30, 1913.

UNITED STATES PATENT OFFICE.

EDWIN RAYMOND CULVER, OF CULVER, INDIANA, ASSIGNOR TO CULVER MILITARY ACADEMY, OF CULVER, INDIANA, A CORPORATION OF INDIANA.

SLEEPING-PORCH.

1,074,103.

Specification of Letters Patent. Patented Sept. 30, 1913.

Application filed July 8, 1912. Serial No. 708,096.

To all whom it may concern:

Be it known that I, EDWIN RAYMOND CULVER, a citizen of the United States, residing at Culver, in the county of Marshall and State of Indiana, have invented a certain new and useful Improvement in Sleeping-Porches, of which the following is a full, clear, concise, and exact description, reference being had to the accompanying drawings, forming a part of this specification.

My invention relates to porches such as are provided with beds or couches for sleeping in the open air.

The object of my invention is to provide a sleeping porch which is readily accessible from the room with which it is associated and one which is provided with movable partitions or windows which may be readily adjusted by the occupant of the porch from his position on his bed or couch.

The windows of my preferred form of sleeping porch are counterbalanced in such a manner that the occupant can, after getting into bed, by pulling a cord or rope close the window between his bed and the room with which the sleeping porch is connected, at the same time automatically opening the window between his bed and the open air. When the occupant is ready to arise, the outside window is closed, whereupon the window between himself and his dressing room is automatically opened. It will thus be seen that a person wishing to occupy the sleeping porch may disrobe in a warm room and get into bed. He then closes the window between himself and the dressing room, thereby automatically opening the outside window. Reversing the process on arising, puts him back into his warm room.

The opening for the outside window is preferably made high enough so that the sunlight may flood the entire interior of the porch. In the form of sleeping porch herein shown and described ventilators are provided to prevent stagnant air from collecting in the space above the window sashes.

Other advantages of the sleeping porch of my invention will appear as this specification progresses.

My invention will be more clearly understood by reference to the accompanying drawings, in which—

Figure 1 is a perspective view of two sleeping porches of my invention opening

into the same room; Fig. 2 is a vertical cross-sectional view of a sleeping porch of my invention taken on the line 2—2 of Fig. 3; and Fig. 3 is a horizontal sectional view of the window sashes and their frames taken on the line 3—3 of Fig. 2. In order to more clearly illustrate the operation of the counterbalanced window sashes, the devices for raising and lowering the window sashes are shown in this figure.

Similar numerals refer to similar parts throughout the several views.

In Fig. 1, I have shown two sleeping porches opening into the same room. In this embodiment of my invention the beds or couches are disposed with the heads adjacent to each other. As shown clearly in Figs. 2 and 3, the sleeping porch is provided with an outside wall 1 and a partition 2 separating the sleeping porch from the room with which it is associated. The wall 1 is provided with a window 3 and the wall 2 is provided with the window 4. Chains 5 and 6 passing over suitable pulleys 7, 8, 9 and 10 are connected to each of the windows in such a manner that when one of the windows is raised the other window is automatically lowered and vice versa. These chains are secured to the window sashes in any suitable manner.

As shown in Figs. 1 and 2, the bed or couch 11 is raised above the floor, allowing the warm air from the room with which the sleeping porch is connected to circulate freely under the bed. Heating radiators may be disposed in the space under the bed or a system of shelves may be provided to occupy this space, if desired.

The warm air from the room is prevented from getting above the bed by a canvas 12 which is stretched over the mattress 13 and under the springs 14, as shown in Fig. 2. The warm air thus confined in the compartment below the bed structure effectively keeps the bed at a comfortable temperature while the occupant may have the advantage of the outside air. Between the two sleeping porches and above the tops of the window frames 15 and 16 is the ventilator 17, which prevents stagnant air from collecting in the well above the window frames. It should be noted that the opening for the window 3 is sufficiently high to allow sunlight to flood the entire interior of the sleeping porch.
